UNITED STATES PATENT OFFICE.

WALTER S. PAYNE, OF TITUSVILLE, PENNSYLVANIA.

SERVICE-COCK.

SPECIFICATION forming part of Letters Patent No. 292,349, dated January 22, 1884.

Application filed August 9, 1882. Renewed December 20, 1883. (No model.)

To all whom it may concern:

Be it known that I, WALTER S. PAYNE, of Titusville, in the county of Crawford and State of Pennsylvania, have invented certain 5 new and useful Improvements in Service-Cocks; and I do hereby declare that the following is a full, clear, and exact description of the invention, which will enable others skilled in the art to which it appertains to 10 make and use the same, reference being had to the accompanying drawings, which form a part of this specification.

Figure 1 is a longitudinal vertical sectional view. Fig. 2 is a vertical cross-section on 15 the line $x-x$, Fig. 1; and Fig. 3 shows in perspective the several parts constituting my invention detached from each other.

Corresponding parts in the several figures are denoted by like letters of reference. 20 This invention relates to what is known as a "corporation-cock," which is used for shutting off water at the street-main while making connection to the cock at the sidewalk, or in case the service-pipe in the street between 25 the main and the curb-box should burst; and it consists in certain improvements in the construction of the same, which will be herein-after fully described, and particularly pointed out in the claim.

30 In the drawings hereto annexed, A represents a ring having an interior screw-thread, and provided at one end with a flange, B.

C is a short exteriorly-threaded piece of pipe, terminating in a bulb, D, which is 35 closed by a plate, E, the projecting edge of which forms a flange, F. The face of plate E is ground true, and is provided with a series of radial slots, G.

H is a short threaded pipe, of the same diameter as pipe C, and terminating, like the latter, in an enlarged chamber, I, which is screw-threaded on the outside, as at J, so as to be capable of being screwed into the ring or band A.

45 Between the pipe H and chamber I is formed a seat, K, to receive a wrench, by which the cock may be operated. The chamber I is

closed by a plate, L, which is ground true, so as to correspond with the plate E previously described, and provided with a series of slots, 50 M, which may be made to register with the slots G. The face of plate L is provided with a forward-projecting stud, N, fitting in a notch, O', in the flange F of plate E, thus permitting said plate L to be turned sufficiently to cause 55 the slots G M to register, or to close them, as the case may be. The pipe C is passed through ring A until the flange F abuts against the flange B of said ring. The enlarged portion or chamber I of pipe H is then inserted 60 into the ring, and screwed down until the face-plates E L are closely in contact with each other, the stud N fitting, as described, in notch O. The cock, which is suitably connected to the service-pipe, may be opened or 65 closed by applying a wrench to seat K and turning it slightly. The pressure of water keeps the cock packed by forcing the face-plates L E in contact with each other, and said slotted plates also serve to prevent any 70 gross impurities—such as fish—to enter the service-pipe from the street-main.

My improved service-cock is simple, convenient, light, and inexpensive, and is not liable under any circumstances to get out of 75 order.

I claim and desire to secure by Letters Patent of the United States—

As an improvement in service-cocks, the combination of the ring A, having flange B, 80 pipe C, having bulb D, closed by a radially-slotted plate, E, having flange F, provided with notch O, and the pipe H, having exteriorly-threaded enlarged portion or chamber I, seat K, and radially-slotted plate L, having stud 85 N, all arranged and operating substantially as described, for the purpose set forth.

In testimony that I claim the foregoing as my own I have hereto affixed my signature in presence of two witnesses.

WALTER S. PAYNE.
